DESIGN FOR AN EMBALMING APPARATUS

John B. Turner, II, Robert L. Thompson, and Everett W. Waters, Cedar Rapids, Iowa, assignors to Turner Company, Cedar Rapids, Iowa, a corporation of Iowa

Application May 1, 1940, Serial No. 92,070

Term of patent 7 years

To all whom it may concern:

Be it known that we, John B. Turner, II, Robert L. Thompson, and Everett W. Waters, citizens of the United States, residing at Cedar Rapids, in the county of Linn and State of Iowa, have invented a new, original, and ornamental Design for an Embalming Apparatus, of which the following is a specification, reference being had to the accompanying drawing, forming part thereof.

The single figure of the drawing is a front view

in perspective of an embalming apparatus showing our new design.

The other side of the article is substantially like the side shown and the rear is substantially plain.

We claim:

The ornamental design for an embalming apparatus, as shown and described.

JOHN B. TURNER, II.
ROBERT L. THOMPSON.
